UNITED STATES PATENT OFFICE.

OTIS A. MYGATT, OF NEW YORK, N. Y.

DESIGN FOR A SHADE, REFLECTOR, OR SIMILAR ARTICLE.

41,241.

Specification for Design.

Patented Mar. 14, 1911.

Application filed June 5, 1908. Serial No. 436,985. Term of patent 14 years.

To all whom it may concern:

Be it known that I, OTIS A. MYGATT, a citizen of the United States, residing at New York, in the county of New York and State of New York, have invented a new, original, and ornamental Design for a Shade, Reflector, or Similar Article, of which the following is a specification, reference being had to the accompanying drawing, forming part thereof.

The drawing is a side elevation of a shade or reflector embodying my design.

My design consists of a shade, reflector, or similar article having a body portion beneath the collar proper in the form of

a cone, the middle portion in the form of a cone having a sharper angle to the axis of the shade, and the lower skirt portion in the shape of a cylindrical vertical sided portion; all three divisions of the shade being covered with prisms lying in the planes of the axis of the shade.

I claim—

The ornamental design for a shade, reflector, or similar article, as shown and described.

OTIS A. MYGATT.
